UNITED STATES PATENT OFFICE.

PARMER DORSEY, OF WICHITA, KANSAS, ASSIGNOR TO THE IMPERIAL BRASS MANUFACTURING COMPANY, OF CHICAGO, ILLINOIS, A CORPORATION OF ILLINOIS.

STEAM-ENGINE LUBRICATOR.

Application filed June 3, 1925. Serial No. 34,535.

My invention is concerned with apparatus for the lubrication of steam engines and locomotives, and is designed to produce a device of the class described which can be readily 5 filled with oil without disturbing its action and without the necessity of stopping to drain out the water accumulated in the reservoir and to be replaced by the oil.

It is also concerned with such a device in 10 which it can be readily filled with oil, and without the possibility of pumping any air into the reservoir in case the supply of oil should be exhausted before the reservoir is filled.

15 It is finally concerned with such a device in which oil can, when desired, be pumped directly and in quantity to some part to be lubricated, such as the air pump cylinder, without the necessity of its passing through 20 the lubricator.

To illustrate my invention, I annex hereto two sheets of drawings, in which the same reference characters are used to designate identical parts in all the figures, of which,—

25 Fig. 1 is a central vertical section on the line 1—1 of Fig. 2, through a portion of a lubricator having my invention applied thereto;

Fig. 2 is a view partly in section on the line 30 2—2 of Fig. 1;

Fig. 3 is a view of the lubricator proper in section on the line 3—3 of Fig. 4; and

Fig. 4 is a view in section on the line 4—4 of Fig. 3.

35 Figure 5 is a sectional view showing a modification.

Referring first to Figs. 3 and 4, I have in these figures shown, except as hereinafter described, an old construction of a sight-feed 40 lubricator, on which my invention is an improvement. Various forms of such sight-feed lubricators can be employed, but the one illustrated consists of a generally cylindrical reservoir 10 which is provided at one end with a valve connection 11 which may or may not 45 be employed, and at the other end with a connection nut 12, into which the outlet end 13 of the force feed pump subsequently to be described can screw. The reservoir 10 has ex- 50 tending vertically through the same a plurality of preferably integral tubes 14, three being shown, and it will be understood that one or more of these tubes may be employed as desired. At the bottom of each of these 55 tubes is located a sight glass 15 and a nipple

16 adapted to be closed or regulated at its bottom by a needle valve 17, so that the rate of the feed of the oil, drop by drop, upward from the nipple 16 can be regulated in the customary manner. Above the reservoir 10 60 is mounted a steam casing 18 which is provided with a connection 19 to the boiler, said connection 19 being provided with a valve seat 20 so that the valve 21 can co-operate therewith to close off the boiler pressure when 65 desired. From the bottom of the steam casing 18, there is located a passage 22 having a valve seat 23 therein, so that the passage may be closed by the valve 24 as desired, and the passage 22 is extended down into the reservoir by the passage 25 located beyond the valve seat, and preferably formed on the back of the central tube 14. Each of the tubes 14 is provided at its upper end with an outlet, the outlet 26 of the central tube only being 70 shown in full. Part of the outlets 27 for the outer tubes 14 are seen in Fig. 3. Each of these outlets has connected with the upper portion thereof one of the three pipes 28 extending upward into the steam casing 18, 75 and in practice it will be understood that the water of condensation from the boiler stands in the casing 18 and passes down through the passages 22 and 25 to the reservoir, displacing the oil therein to the upper portion, 80 whence it descends under pressure through the tube 29 opening into the top of the reservoir to the horizontal passage 30 in the bottom of the reservoir casting, whence the oil can pass laterally through the ports 31 into 85 each of the pockets 32 associated with the valves 17. The sight-feed lubricator thus far described is of a well known construction, and, per se, constitutes no part of my invention, which may employ other similar sight- 90 feed lubricators.

As a preferred form of a force feed pump, I employ that shown in Figs. 1 and 2, where it will be seen that the outlet 13 is part of a casting 33 having four projections, as it 100 were, the projection 34 serving to enclose the barrel 35 of the pump, which has the solid piston 36 adapted to reciprocate therein through the customary stuffing boxes 37, 37. The piston is preferably manipulated by the 105 handle 38, preferably operating as a lever of the second class, with the fulcrum 39 formed by the link 40 pivoted at its other end to the yoke 41, which embraces the projection 34 and is secured in any desired position of ad- 110

justment by the nut 42 threaded on said projection. With this arrangement, it will be understood that the handle 38 can be set at any convenient angle for operation in the particular installation in which it is used. The top projection 43 is internally threaded and has screwed thereinto the check-valve casing 44, which contains the spring-pressed check valve 45 co-operating with a seat in said casing, and toward the upper end thereof, I form the annular seat 46, upon which is fitted the bottom of the tank 47 which contains the supply of oil to be pumped into the reservoir 10 when it is needed. On the top of this casing 44, I form the valve seat 48 with which cooperates the float valve 49, which is held from displacement by the wire cage 50 secured in the nut 51 screwed on the upper end of the valve casing 44 and serving to hold the tank 47 in place.

The third projection 52 has on its outer end the threaded portion 13, and has located in the interior thereof the customary spring-pressed check valve 53 operating in the customary manner. The pump barrel 35 is connected with the outlet by the port 54, seen in Fig. 1, which is adapted to be closed by the valve 55 having the stem threaded through the packing-gland structure 56 threaded into the casting 33, as clearly shown in Fig. 1, and provided with the handle 57 by which the valve can be closed when desired. The projection 58 has threaded into its lower end the connection 59 by which it is secured to a pipe 60 which may be extended to the steam cylinder 61 of the air pump 62, and in this pipe 60, I locate the cock 63, which can be opened or closed as may be desired.

In the reservoir 10, I screw or otherwise secure the valve casing 65, which has the valve seat 66 formed therein and adapted to be closed by the sliding valve 67 having its inner end in the hollow bolt threaded into the casing 65, and having the helically-coiled expanding spring 69 located therein beneath the plunger valve 67, so that said valve will be held closed by a pressure varying with the amount that the bolt 68 is screwed in. In case it is desired to close this valve against any possible pressure, I provide on it an annular shoulder 70, against which the end of the bolt 68 engages when it is screwed in to the limit. The outlet passage 71 may be provided with any suitable connection if it is desired to carry the water of condensation to some particular point instead of discharging it directly.

The operation of my improved device is as follows:

Assuming that the supply of oil in the reservoir has been used up until the water has reached the level of the top of the tube 29, and assuming that the bolt 68 has been adjusted so as to take a little more than the boiler pressure to open it, then all that is

necessary is to operate the pump handle with the cock 57 open, the cock 63, and the valves 17, 21 and 24 closed. The oil from the tank 47 will be forced into the reservoir, rising to the top and displacing the water in the reservoir beneath it, and forcing it out through the outlet 71, the pressure produced by the pump being sufficient to overcome the resistance of the spring 67. This pumping is continued until the reservoir is filled with oil, as indicated by its being forced out through the outlet 71, or as may be seen in the gauge glass which is usually employed in these devices. If it should happen that the oil in the tank 47 is exhausted before the reservoir is filled, the valve 49 is seated by gravity and the suction of the pump piston, so that air cannot be pumped into the reservoir, which would be highly objectionable, and the resistance created to the outward movement of the piston 36 will indicate to the operator that his oil supply in the tank 47 is exhausted, so that he will refill it before further operation. When the reservoir is filled, the valves 17, 21 and 24 are again opened, and the automatic sight-feed lubrication will be resumed. In case it is desired to lubricate the cylinder 61 directly, the cock 55 is closed and the cock 63 is opened, when the operation of the handle 38 will pump oil directly to the cylinder 61. Similarly, by screwing up the bolt 68 to close the valve 67 immovably, and closing the valves 21, 24 and all but the desired one of the valves 17, oil can be forced in quantity to the cylinder connected with the valve 17 that has been left open, so that in case of emergency, any cylinder can be copiously lubricated almost immediately.

In Fig. 5, I have illustrated an alternative construction to take the place of the valve 49, and prevent air being pumped into the reservoir. In this case, I omit the valve seat 48 and the cooperating ball 49, and its casing 50, and modify the valve 45, lettered in the modification 45^a, but omitting the spring to hold it seated, and by arranging it to rest by gravity upon the top of the retaining sleeve 72 screwed into the bottom of the check valve casing 44 close enough to its seat so that while the check valve 45^a is normally open, the pressure of the oil when the piston 36 is moved inward will lift it and seat it before the spring associated with the check valve 53 yields to permit the oil to be forced out. When the oil in the tank 47 is exhausted, the air that would then pass below the valve 45^a does not furnish a medium by which the valve 45^a can be lifted to its seat, and the piston 36 cannot compress the air in the tank 47 sufficiently to overcome the resistance of the spring associated with the valve 53, so that neither oil nor air can be pumped after the oil supply falls below the valve 45^a. To prevent the valve 45^a from seating on the top of the retaining sleeve 72, and thus preventing the oil and air from pass-

ing the valve 45^a when it is down, I form one or more recesses 73 in the top of the sleeve 72.

While I have shown and described my invention as embodied in the form which I at present consider best adapted to carry out its purposes, it will be understood that it is capable of modification, and that I do not desire to be limited in the interpretation of the following claims except as may be necessitated by the state of the prior art.

What I claim as new, and desire to secure by Letters Patent of the United States, is:

1. In a lubricator, the combination with a reservoir normally containing oil in its upper part and water in its lower part, of means for supplying normal oil-feeding pressure to the reservoir, sight-feed apparatus to carry the oil drop by drop to the part to be lubricated, a supply tank, a force pump connected to draw its supply from the tank, connections from the discharge of the pump to the reservoir, a three-way valve casing having one end screwed into the reservoir and the directly opposite end internally threaded, a hollow bolt closed at its outer end screwed into said opposite end, a valve seat located in the passage between said ends, an outlet between the valve seat and the bolt, a sliding valve adapted to co-operate with said seat and having its outer end in the hollow bolt, and a helically-coiled expanding spring in the bolt beneath the valve, substantially as and for the purpose described.

2. In a lubricator, the combination with a reservoir normally containing oil in its upper part and water in its lower part, of means for

supplying normal oil-feeding pressure to the reservoir, sight-feed apparatus to carry the oil drop by drop to the part to be lubricated, a supply tank, a force pump connected to draw its supply from the tank, connections from the discharge of the pump to the reservoir, means for closing said connections, a pipe leading from the discharge of the pump to deliver the oil from the force pump at a point distant from the reservoir, and a shut-off cock in said pipe.

3. In a lubricator, the combination with a reservoir normally containing oil in its upper part and water in its lower part, of means for supplying normal oil feeding pressure to the reservoir, sight feed apparatus to carry the oil drop by drop to the part to be lubricated, a supply tank, a force pump, connections from the force pump to the reservoir including an automatic closing check valve opening when sufficient pressure is applied thereto by the force pump, and connections from the supply tank to the force pump which prevent pumping air into the reservoir when the supply of oil in the tank is exhausted, said connections comprising a passage containing a downwardly facing valve seat, a valve therein normally held away from the seat, but forced upward against it by the pressure of the oil when the pump piston is forced inward, and a supporting sleeve in the passage for the valve having a recess in its upper end for the purpose described.

In witness whereof, I have hereunto set my hand this 27th day of May, 1925.

PARMER DORSEY.
